AMALGAMATOR

FIG. II.

FIG. IV.

FIG. III.

By Whitehead & Vogl
Per Earle Whitehead Attorney

Inventor

JOHN F. WELSH

UNITED STATES PATENT OFFICE

JOHN F. WELSH, OF PUEBLO, COLORADO

AMALGAMATOR

Application filed January 17, 1928. Serial No. 247,323.

This invention relates to amalgamators for recovering values from placer material, comminuted ores and the like and has for an object to provide, in an amalgamator having 5 mercury-retaining riffles, means for causing material, to be treated, to flow across said riffles by centrifugal force.

A further object is to provide, in an amalgamator, means for efficiently controlling, as 10 to speed and quantity, the passage over the riffles of the material to be treated.

A further object is to provide, in an amalgamator, simple means for adapting the device to the handling of either coarse or fine 15 material.

A further object is to provide an amalgamator in which electricity may be readily and efficiently applied in aid of the recovery of values and the provision of means, in such 20 amalgamator, for such application.

Further objects are to provide an improved amalgamator simple, durable and compact in construction, efficient in operation as to quantity of material handled, the recovery of values 25 therefrom and as to the saving in water and power used in operation.

Other objects will appear from the following specification and claims illustrated in the accompanying drawing, in which like characters of reference indicate corresponding 30 parts throughout and in which

Figure I is a view partly in elevation and partly in section of the improved amalgamator.

Figure II is a detailed view in vertical section showing the lower part of the amalgamator with the false bottom or adapter in place.

Figure III is a detail showing the shape or structure of the riffles and

Figure IV is a section on line $a-a$ of Figure I, illustrating the electrifying means.

The invention may be generally described as a bowl with annular riffles upon the inner walls thereof, provided with means for holding a charge of mercury at the bottom, means for revolving the bowl at desired speeds for filling the riffles with mercury, by means of centrifugal force of the revolution of the bowl and means for supplying the material 45 to be treated to the bottom of the bowl from

whence it will be thrown up across the annular riffles by the centrifugal force of the revolution of the bowl and in passing across such riffles the values will be drawn from the material being treated by the mercury in 55 manner similar to the action of the mercury in the riffles at the bottom of a sluice, the materials passing out over the top of the bowl after the values have thus been extracted. Means are also provided in the bottom of the 60 bowl for the recovery of some of the values therein. Means are also provided for supplying electricity for activating the mercury at the bottom of the bowl.

Upon any suitable support the amalgamator is revolvably mounted, as upon shaft 2, revolvable in a bushing 3 and terminating in the bottom of the bowl 4 keyed thereto by the pin 5, so as to cause revolution of the bowl 4 with the shaft 2. Suitable bearings 6 are provided and the joint between the shaft 2 and the bowl 4 is tight to prevent leakage.

The bottom of the bowl 4 is provided with a chamber 7 having an annular recess 8. Annular grooves 9 and riffles 10 are formed in the inner wall of the bowl, the bowl being formed with flaring sides as clearly shown in the drawings.

The bowl is preferably provided with a 80 rolled upper edge 11 so as to prevent the overflow from the bowl flowing down on the outside wall of the bowl.

A suitable casing to prevent splash and to confine and drain off the tailings is provided 85 consisting of a wall 12, a suitable top 13 with a central aperture 14 for accommodation of the material supply pipe hereafter described, a bottom 15 sloping into a drainage outlet 16 and having a collar 17 surrounding the bowl 90 and terminating within and beneath the rolled upper edge of the bowl whereby the overflow from the bowl is deposited within the casing outside of the collar 17, which collar prevents the overflow from running down 95 around the bowl and retains the same within the chamber until it flows out of the drain 16.

The bowl may be revolved by means of the pulley 18 operated by the belt 19 connected with any suitable source of power not shown. 100

A suitable drain is provided in the bottom of the chamber 7, which drain is normally closed by the plug 20.

For electrifying the mercury a band 21 of suitable material is provided around the outside of the base of the bowl opposite the chamber 7 and suitable means such as copper pins 22 are positioned with the heads preferably imbedded in the band 21 and the points extending through the walls surrounding the chamber 7 and into the chamber 7 so that the points of the pins will contact with the mercury in the chamber 7. Any suitable electrifying means may be provided, as an armature coil 23, a brush 24, grounds 25 and 26 and a battery 27, providing a circuit as indicated.

It will be noted that the annular grooves 9, preferably extend, as clearly shown in Figure III, above the points 10 of the riffles so as to form a suitable recess for the reception and retention of the mercury and the values amalgamating therewith.

When it is desired to operate with very fine material a false bottom 28 is provided which separates the chamber 7 from the inside of the bowl proper, the bottom of the amalgamator then being the false bottom 28 instead of the bottom of the chamber 7 which is the bottom of the amalgamator when coarser material is being operated upon. The false bottom is provided with an outlet tube 29 adapted to connect with a plug 30 in the outlet from the bottom of chamber 7. When the fine material is being treated, the plug 30 is used for stopping this outlet and at the same time stopping the end of the outlet tube 29. The false bottom 28 may be affixed by means of a screw 21 or any other suitable means.

To furnish the material to be treated, a pipe 32 is provided terminating near the bottom of the bowl, to which pipe the material may be supplied to any suitable point not shown, thence flowing through the pipe to the bottom of the bowl.

In operating, mercury is placed in the chamber 7, the amalgamator is revolved, which results in throwing a portion of the mercury up along the sides of the bowl and into the grooves 9 therein, some of the mercury being retained in the outer portion of the chamber 7 and in the recess 8, the material to be treated is then supplied through the pipe 32, together with the required amount of water to make the same flow as required for the amalgamating operation, the proportions of water, material and amount of mercury being determined according to approved practice. As the material drops from the pipe 32 into the bottom of the bowl, the centrifugal force of the revolution of the bowl will throw the material up over the annular riffles in the wall of the bowl and as it passes over the riffles and the mercury in

the grooves 9 the values will be gathered from the material by the mercury in the grooves, the tailings passing out over the rolled edge 11 and thence out through the tail drain 16.

When it is desired to make a cleanup, the amalgamator is stopped, whereupon the mercury in the grooves 9 will drop down to the bottom of the bowl from whence it can be drawn off by the removal of plug 20 if the chamber 7 is being used, or by the removal of the plug 30 if the false bottom 28 is being used.

During the amalgamating operation, and prior thereto if desired, the current is run through the electrifying means above described, resulting in the activating of the mercury by the electricity from the pins 22. If the current be turned on while all of the mercury is in the chamber 7, all of the mercury will be activated. If the current be not turned on until after a portion of the mercury has been thrown into the grooves 9 by the revolution of the amalgamator, the mercury in the grooves will be activated only to the extent of the electric current transmitted from the band 21 and the pins 22 through the walls of the bowl to the mercury in the grooves. The mercury retained in chamber 7 will be directly activated by contact with the pins 22.

Any suitable means not shown may be provided for regulating the speed of revolution of the amalgamator and the speed of the revolution will obviously determine the speed at which the material will pass over the riffles 10 and will correspondingly and partially regulate the thickness of the material in its passage over the riffles. The consistency of the material to be treated will be regulated by the amount of water supplied thereto and it will be obvious that in practice a very fine adjustment may be obtained by the relative regulation of the consistency of the material and the speed of revolution of the amalgamator, such fine adjustment making possible a most efficient treatment of material, a saving in the amount of water used for such treatment and an adaptability of the device to various kinds of material.

It will also be obvious that the water may be readily recovered from the tail drain 16 and supplied again to new material to be treated, thus accomplishing a further economy in the matter of the use of water, which is a vital consideration at many places at which it is desirable to operate an amalgamator.

Numerous changes may be made in the detailed construction within the scope and spirit of the invention and the appended claims.

I claim:

1. A rotatable amalgamator having an inferiorly rifled bowl shaped portion, a remov-

able bottom therein, a circular chamber beneath said bottom and having a peripheral recess, whereby the rifled bowl shaped portion may be used both separately for the treatment of fine material and in combination 5 with said recessed chamber for the treatment of coarser material.

2. A rotatable amalgamator having an interiorly rifled bowl shaped portion, a removable bottom therein, a circular chamber 10 beneath said bottom and having a peripheral recess, a closable drain in the bottom of said chamber, means for draining said removable bottom into said drain, when said bottom is in place.

15 3. A rotatable amalgamator having an interiorly rifled bowl shaped portion, a removable bottom therein, a circular chamber beneath said bottom and having a peripheral recess for retaining mercury and means for 20 electrically activating such mercury.

4. A rotatable amalgamator having an interiorly rifled bowl shaped portion, a removable bottom therein, a circular chamber beneath said bottom and having a peripheral 25 recess for retaining mercury and means for electrically activating such mercury, said means comprising a band of conductive material around the periphery of the wall of said chamber and members of similar material passing through the walls of said chamber and connecting said band with the interior of said recess.

In testimony whereof, I affix my signature.
JOHN F. WELSH.
